[57] CLAIM

The ornamental design for a simulative bubble blower, as shown and described.

DESCRIPTION

FIG. 1 is a top plan view of a simulative bubble blower showing my new design;

FIG. 2 is a side elevational view thereof, a side elevational view of the other side constituting a mirror image of what is shown in FIG. 2;

FIG. 3 is a front elevational view thereof;

FIG. 4 is a rear elevational view thereof; and

FIG. 5 is a bottom plan view thereof.
